NON-HYDROSCOPIC CONDIMENT DISPENSER

Fred M. Trecartin, 8150 SW. 54th Ave.,
Miami, Fla. 33143

Filed Apr. 10, 1972, Ser. No. 242,902

Term of patent 14 years

Int. Cl. D7—06

U.S. Cl. D7—53

FIG. 1

FIG. 2

FIG. 3

FIG. 1 is a side elevation of a non-hygroscopic condiment dispenser, showing my new design.

FIG. 2 is a top plan view thereof.

FIG. 3 is a bottom plan view thereof.

I claim:

The ornamental design for a non-hygroscopic condiment dispenser, as shown.
